Inventor:

FRIDOLF FRANKEL

By George Bayard Jones, atty.

UNITED STATES PATENT OFFICE.

FRIDOLF FRANKEL, OF STOCKHOLM, SWEDEN.

METAL SOUNDING BOARD FOR PIANOS.

Application filed September 25, 1922, Serial No. 590,229, and in Germany November 2, 1921.

In my copending application Serial No. 368,220 I have described a metal sounding-board for pianos the edge portions of which are contracted or shortened relatively to the portions within said edges whereby the sounding-board obtains a certain cup-shape or convexity, and there is simultaneously produced a stress or tension in the board which in turn produces an increased 5 sounding power. According to one embodiment the sounding-board is provided with corrugations or bent-up folds or ribs having approximately V-shaped cross section and projecting above the front side of the sounding-board, each of said ribs being pressed together at its ends 10 at the edges of the sounding-board, so that the cross section of said ends 4 of the ribs becomes slightly narrower than that of the intermediate portions of the ribs, and in this manner the edges of the sounding-board become contracted or shortened, so that the portion within said edges obtains a certain cup-shape or convexity, and simultaneously, 15 a certain tension will be produced in the same.

According to the present invention there is provided on the side of the plate or sounding-board opposite to that from which the 20 said corrugations or ribs project, ribs or laths 6, for instance of wood. Said ribs or laths 6 are secured to the plate in suitable manner, for instance, as illustrated in Figs. 4 and 5, by means of screws 7 which pass 25 through the plate on either side of the corrugations or ribs 2 and are screwed into the laths 6, said screws thus being close to the crossing points of the corrugations 2 with the laths 6. Said laths 6 may also preferably be secured to the plate by means of a 30 suitable cement or the like.

The ribs or laths 6 will of course maintain the substantially plane portions of the plate or sounding-board between the corrugations 35 2 in proper position in alignment with one another, and said laths will thus eliminate the tendency of said portions to become displaced more or less relatively to one another in a direction perpendicular to the plate 40 owing to the tension in the same. The corrugations 2 and the laths 6 thus form together what may be termed a lattice-work 45 for the approximately plane portions of the plate and thus a guide for the same, and simultaneously the sounding-board obtains 50 an increased bearing power or spring. The lattice-work divides the sounding-board into a large number of squares or panels, each 55 panel forming, so to speak, a diaphragm 55 which vibrates more freely than the surrounding ribs or laths, and thus more freely than the sounding-board as a whole. I have 60 found that sounding-boards constructed in this manner become more sensitive and are 65 therefore able to receive and to intensify a 70 larger number of overtones than sounding-boards constructed in the usual manner.

As described in my copending patent application above referred to, the sounding-board is formed of a whole continuous metal plate 1 in which there are formed corrugations or bent-up folds or ribs 2 which have an approximately U-shaped or V-shaped 75 cross section. The said ribs 2 preferably project above the front side of the sounding-board 1, to which side the bridge or bridges 5 over which the strings are stretched, are secured. When attaching the board 1 to the fastening rim 3 by soldering or in any other suitable manner, each rib 2 is squeezed or 80

I claim:

1. A metal sounding-board for pianos provided with bent-up ribs having approximately V-shaped cross section and projecting 85

above the front side of the sounding-board, each of said ribs being pressed together at its ends at the edges of the sounding-board, for the purpose of producing contractions of the edge portions of the sounding-board, laths being secured to the opposite side of the board substantially crosswise to said ribs.

2. A metal sounding-board for pianos provided with bent-up ribs having approximately V-shaped cross section and projecting above the front side of the sounding-board, each of said ribs being pressed together at its ends at the edges of the sounding-board, for the purpose of producing contractions of the edge portions of the sounding-board, laths being secured to the opposite side of the board, said laths extending transversely to the direction of the ribs on the front side of the board, said laths extending transversely

to the direction of the ribs on the front side of the board.

3. A metal sounding-board for pianos provided with bent-up ribs having approximately V-shaped cross section and projecting above the front side of the sounding-board, each of said ribs being pressed together at its ends at the edges of the sounding-board, for the purpose of producing contractions of the edge portions of the sounding-board, laths being secured to the opposite side of the board, said laths extending transversely to the direction of the ribs on the front side of the board and being rigidly secured to the sounding-board adjacent the crossing points of the ribs with the laths.

FRIDOLF FRANKEL.
